FLY SWATTER

Filed Sept. 16, 1927

Patented Mar. 19, 1929.

1,705,872

UNITED STATES PATENT OFFICE.

GEORGE A. MAHARG, OF MOOSE JAW, SASKATCHEWAN, CANADA.

FLY SWATTER.

Application filed September 16, 1927. Serial No. 220,035.

The invention relates to improvements in fly swatters and an object of the invention is to provide a swatter mounted on the entrance door of a building, and adapted to be actuated to kill or scare the flies congregated at the outer side of the door and arranged so that one can operate the swatter from either the inside or the outside of the door prior to opening the same.

10 A further object is to position the swatter adjoining the upper part of the door where the majority of flies congregate and to position the hand grips which actuate the swatter at the inner and outer sides of the 15 door and in a location adjoining the usual door hand grip.

A further object is to construct the swatter so that it will be held normally in a down-hanging position and will have considerable sweep when actuated to strike or 20 scare the flies at the upper part of the door and lintel.

25 A further object is to construct the device in a simple, durable and inexpensive manner and so that it can be readily assembled and placed on the door and without requiring to change the existing door structure.

With the above more important objects in view, the invention consists essentially in the 30 arrangement and construction of parts hereinafter more particularly described, reference being had to the accompanying drawing, in which:—

Figure 1 is an exterior view of a screen 35 door with my device applied thereon.

Figure 2 is an enlarged detailed vertical sectional view at 2—2' Figure 1, certain parts being shown in side elevation.

40 Figure 3 is an enlarged detailed vertical sectional view at 3—3' Figure 1.

Figure 4 is a perspective view of the hinge and associated parts.

In the drawing like characters of reference indicate corresponding parts in the several figures.

45 This swatter is designed to be mounted on the exterior of the entrance door of a building, such as on the screen door of a house, and it is intended that the swatter be actuated when desired by one entering or coming out of the house in order to kill and scare the flies and other insects which usually congregate around the top of the door in a location adjacent the frame lintel.

50 The screen door 1 is of the customary

type, being hinged at 2 to the frame 3 and being supplied with the usual opening handle 4. In a location adjacent the top of the door and at the hinged side thereof I locate a bearing 5, which supports rotatably one 60 end of a cross shaft 6, the other end of the shaft being received rotatably within the eyes 7 and 8 of a hinge wing 9, the wing being fastened in the usual manner by screws 10 to the door. A lever forming, second hinge wing 11 is provided and this has the eyes 12 and 13 thereof mounted on the shaft in a location between the eyes 7 and 8 and the said eyes 12 and 13 are fastened to the shaft by pins 14 and 15.

70 The swatter 16 which I provide is carried by and secured to the shaft and takes normally a down-hanging position as best shown in Figure 1. The swatter is formed from a number of similar suitably spaced 75 spring wire rods 17, which have their upper ends received within a channel shaped strip 18, to which they are permanently attached, such by soldering or welding. On the rod 6 I mount an attaching strip 19, 80 which is bent around the rod and has the ends thereof spaced apart and receiving the strip 18. Comparatively small bolts 20 are utilized to fasten the strip 18 to 19 and the arrangement is such that by undoing these 85 bolts one can readily remove the swatter for repair or other purposes. The strip 19 is fastened permanently to the shaft by suitably spaced rivets 21.

85 The hinge 11 and the swatter normally 90 hang down, being held in their downhanging position by a coil spring 22 applied on the shaft between the eyes 12 and 13 and have one end engaging the door and the other end overlying the wing 11. The swatter extends across the door screen and the length of the rods 17 is such that when the swatter is swung upwardly it will strike the upper part of the door and kill and scare any flies or other insects at such point.

95 To operate the swatter I provide the parts now described. To the wing 11 I fasten one end of a pulling line 23, and the pulling line is passed first through a hole 24 formed in the door above the wing and then downwardly through a guide tube 25 suitably secured as by staples 26 to the inner side of the door. The lower end of the pulling line, which extends downwardly beyond the tube, is provided with a hand grip 27. A second 100

105

110

pulling line 28 is passed through an inclined hole 29 provided in the door and has the inner end fastened at 30 to the pulling line 23 and the outer end provided with a hand grip 31. The grips 27 and 31 are at the inner and outer sides of the door respectively and are positioned so that they are within convenient range of the hand when one is entering or going out of the building. I have shown them in a location just above the hand grip 4. I have found that a piano wire serves very effectively as a pulling line.

The guide tube 25 is not essential, as it simply keeps the wire from flapping at the inner side of the door. The device is used in the following way. If one is entering the building and there are flies or other insects congregated on the upper part of the door he will grasp the hand grip 31 and give it a pull before opening the door. This will cause the swatter to fly up and strike the upper part of the door and kill or scare the flies. The door can then be opened and there will be small possibility of flies entering the building.

If one is going out of the building he will pull the grip 27, which operates from the interior to actuate the swatter.

I have indicated at 32 the customary spring catch attached to the frame and utilized for releasably holding the screen door shut, but as such forms no part of my invention I have not considered it necessary to give a detailed description thereof.

35 What I claim as my invention is:

1. The combination with the door of a building, of a fly swatter extending transversely of the door and pivotally carried thereby and pulling grips located at the inside and at the outside of the door and connected to the swatter and adapted, when pulled, to cause the swatter to strike the door.

45 2. The combination with the entrance door of a building, of a swatter crossing the upper part of the door at the exterior and pivotally carried thereby, and presenting

a plurality of normally downwardly extending spring rods and a pulling line connected to the swatter and passing slidably through the door above the swatter and having the end thereof terminating at the inner side of the door in a hand grip.

3. The combination with the entrance door of a building, of a swatter crossing the upper part of the door at the exterior and pivotally carried thereby, and presenting a plurality of normally downwardly extending spring rods and a pulling line connected to the swatter and passing slidably through the door above the swatter and having the end thereof terminating at the inner side of the door in a hand grip, and a second pulling line attached to the former pulling line and extending downwardly slidably through the door and having the outer end thereof terminating in a hand grip.

4. The combination with the entrance door of a building, of a swatter extending transversely across the upper part of the door and having the ends thereof pivotally carried thereby and embodying a plurality of extending suitably spaced spring rods, hanging normally downwardly, a down-hanging lever attached to the swatter, a pulling line secured to the lever and extending slidably through the door in a location above the lever and having the inner end thereof terminating in a hand grip, a second pulling line secured to the former pulling line at the inner side of the door, said second pulling line passing slidably through the door to the exterior thereof and terminating in a hand grip, said hand grips when pulled being adapted to cause the swatter to forcibly strike the upper part of the door and a spring associated with the swatter and adapted to return the same to its down-hanging position after it has struck the door.

Signed at Moose Jaw, Sask., this 20th day of July, 1927.

GEORGE A. MAHARG.
